TION OF MASSACHUSETTS.

ELECTRIC CHANNELING-MACHINE.

1,275,156.

Specification of Letters Patent. Patented Aug. 6, 1918.

Application filed February 2, 1907. Serial No. 355,404.

To all whom it may concern:

Be it known that I, ALBERT BALL, a citizen of the United States, residing at Claremont, in the county of Sullivan and State of New Hampshire, have invented an Improvement 5 in Electric Channeling-Machines, of which the following description, in connection with the accompanying drawings, is a specification, like numerals on the drawings representing like parts.

10 This invention relates to pulsators, and particularly to reciprocating pulsators, being herein shown as applied to tool actuating motors and associated with improvements in channeling or other stone working machines.

15 In order that the principles of my invention may be made fully apparent, I have disclosed one type of embodiment thereof in the accompanying drawings, wherein—

20 Figure 1 is an end view of a channeling machine embodying one form of my invention, the working cylinder or motor and portions of the driving connections for the pulsator being shown in section;

25 Fig. 2 is a side elevation of the mechanism shown in Fig. 1, the compressor and a portion of the pulsator being shown in vertical section, and the standard for the electric motor and other parts being represented 30 in dotted lines as shifted to the opposite end of the machine;

35 Fig. 3 is a plan view of the driving motor for the pulsator and a portion of the means for raising and lowering the working cylinder;

40 Fig. 4 is a vertical sectional view of one form of compressor and pulsator that may be used in connection with the channeling machine;

45 Fig. 5 is a vertical central section of the working cylinder; and

Fig. 6 is a plan view partly in horizontal section of a valve employed in connection with the working cylinder to control the application of pressure to the piston thereof.

Having reference to that single type or embodiment of the invention herein represented, and referring more particularly to

Figs. 1 and 2, the body or frame of the machine to which the invention may be applied, and which is herein shown as a channeling machine, is represented at 1, it preferably having suitable wheels 2 running upon tracks 3. While power may be applied in any suitable manner to the wheels 2, in the present embodiment of the invention I have chosen to employ a separate motor for the purpose represented at 4, which may be an electric or other desired motor of suitable type. Herein the driven shaft thereof has theron a beveled gear 5 meshing (Fig. 2) with beveled gears 6 and 7 mounted upon a worm shaft 8, a clutch 9 being mounted upon said shaft and suitably actuated, as by a hand lever 10, whereby either of the gears 65 may be connected with the shaft and the machine may be driven in either direction or the gears may be disconnected from the shaft and the machine held stationary. Upon the worm shaft 8 are suitably mounted, preferably at the opposite ends thereof, worms 11 and 12 meshing with worm wheels 13 and 14 upon both axles of the machine.

70 By the employment of a separate track feed motor it is possible not only to use small motors upon the machine by dividing the power required for the various operations but a constant as well as independent track movement may be obtained at all times when the machine is working.

75 The operating parts of the machine may be disposed in any desired manner, but preferably there is provided an upright standard 15 mounted for adjustment longitudinally of the machine and for a tilting adjustment 80 to the front or rear upon a preferably horizontally disposed trunnion shaft 16, suitably mounted upon the frame of the machine and preferably extending from end to end thereof. As indicated in Figs. 1 and 2, a 85 clamp box 17 secures the standard to the trunnion shaft and permits movement of the standard longitudinally of said shaft or circumferentially thereof. A side brace 18 is 90 preferably employed to aid in supporting 95 the standard, it being represented in Fig. 2

is diagonally disposed and connected at its upper end to the standard and at its lower end bolted to a sliding clamp box 19 embracing the trunnion shaft 16 and preferably made in two parts united as shown by a lower bolt 20 and an upper bolt 21, which also secures the side brace to the box. As will be apparent, the clamp box may be moved laterally when it is desired to shift the standard, and if an extreme lateral movement of the standard is desired, as to the dotted line position indicated in Fig. 2, the sliding clamp box may be removed and replaced at the right hand side of the standard and the side brace applied to such side of the standard. Any suitable form of brace, if such be regarded as necessary, may be employed.

Referring to Fig. 1, the cross head is suitably mounted as indicated at 22, and has attached thereto preferably a series or gang of tools 23. The cross head may be actuated in any suitable manner, and herein for the purpose is indicated (Figs. 1 and 5) a working piston 24 to the piston rod 25 whereof the cross head 22 and tools 23 are preferably connected. The working piston is suitably mounted for reciprocation in the working cylinder 26, preferably mounted upon the standard 15 and guided (Fig. 3) in suitable vertical ways 27 therein, whereby the said cylinder may be elevated and depressed as desired. When the channeler is working, it is desirable to change the drills after a certain depth of cut, and this can most readily be effected by elevating the working cylinder together with the cross head and drills. This may be done in any suitable manner either manually or otherwise, but in the present embodiment of the invention I have represented the following effective means for raising or lowering the same. Suitably mounted in the framing of the machine is a vertically disposed screw shaft 28 upon which a working cylinder is mounted for movement thereon. To the upper end of the screw shaft is attached (Figs. 1 and 3) a beveled gear 29 having meshing therewith beveled pinions 30 and 31 loose upon a shaft 32 preferably driven by sprocket gearing 33 from the driving motor for the pulsator, as will be more fully described. Upon the shaft 32 between the beveled pinions 30 and 31 is splined a clutch 34 for longitudinal movement whereby either pinion may be made fast to the shaft 32 and the screw shaft 28 thereby driven in either direction. The clutch 34 may be actuated in any suitable manner. Preferably an upright rock shaft 35 is suitably mounted in the frame to the upper end whereof is attached (Fig. 3) a lever 36 suitably connected to a sliding rod 37 connected to the clutch 34. To the lower

portion of said rock shaft may be connected a lever 38 to which a handle 39 may be connected for operation. This handle is shown in Fig. 2 and is slidably mounted and so arranged that it can be grasped at either side of the standard and moved to turn the lever 38 and the rock shaft 35. In this manner the driving cylinder may be raised and lowered by power from any suitable source, the application of such power being suitably controlled as described.

In the present type of the invention a pulsator is preferably employed to operate the working piston, it being herein represented (Figs. 1, 2 and 4) at 40. In the operation of the pulsator air or other fluid is maintained under desired pressure in the system and pulsated, that is, moved backward and forward so as to operate the piston of the working cylinder in the proper manner. Preferably the pulsator is bolted or otherwise suitably secured to the standard 15 and herein at the opposite side thereof from the working cylinder. In this manner the pulsator and the working cylinder may be always preserved equidistant. It is frequently desirable to tilt or incline the operating mechanism of a channeler or other quarrying machine. While if desired other provisions may be made, in the illustrated form of the invention means are employed to tilt the standard 15 with all the parts carried thereby. Upon the framing of the machine (Figs. 1 and 2) is mounted for longitudinal adjustment a bracket 41 to a swinging block 42 whereon is bolted for swinging movement an adjustable brace 43 herein shown as comprising a lower or body part 44, preferably having a nut in the upper end thereof, and an upper screw threaded portion 45 adjustable in said nut and suitably connected to a swinging block 46, herein shown as secured to a portion 47 projecting from the pulsator. By adjustment of the brace 43 it will be apparent that the operating mechanism may be tilted as desired, the brace being moved lengthwise of the machine frame with the standard when desired.

Within the cylinder of the pulsator 40 is mounted for reciprocation a piston 48 having a trunk piston rod 49 connected therewith and suitably actuated in any desired manner as by means of a crank 50 (Fig. 1) within a suitable crank box 51 and mounted upon a shaft 52 having thereon (Figs. 1 and 3) a driving gear 53 actuated by a pinion 54 of a motor 55. While the pulsator may be actuated in any suitable manner, preferably an electric motor such as indicated at 55 is employed, whereby through suitable connections typified by those herein described the pulsator is actuated. Herein the elec-

tric motor 55 is suitably mounted upon the rear of the pulsator for lateral adjustment with reference to the standard as indicated in the dotted line positions in Fig. 2. For 5 this purpose the lower portion of the motor 55 may be adjustably connected to the bearing for the crank shaft 52 and the casing thereof may, as indicated in Figs. 1 and 2, be adjustably connected by bolts 55' or otherwise to the lower portion of the pulsator whereby, viewing Fig. 2, the said motor 55 may be thrown either to the right or left, in 10 order that it may be kept within the line of the standard 15, and hence out of the 15 way of the wall rock whether the standard be mounted at the right hand or left hand end of the machine, viewing Fig. 2. Thus the machine can work close up to the wall rock, the motor 55 being adjusted inwardly 20 from said rock in either position of the standard. The sprocket gearing 33 previously referred to as employed to actuate the screw shaft 28 is herein represented as driven from the crank shaft 52, although 25 it is apparent it may be actuated from any suitable source. The pulsator 40 is suitably connected to the working cylinder 26 in any desired manner and herein (dotted lines Fig. 1) are represented, for the purpose, flexible 30 or jointed metallic, rubber or other suitable connections 56 and 57. While these connections represent the upper and lower portions of the pulsator as connected with the corresponding portions of the working cylinder, 35 it is apparent that such arrangement may be reversed if desired.

at 62 communicating through a valve opening 63 with the upper end of the compressor cylinder, and by means of a vertical passage 64 with the lower end of said cylinder, said upper inlet passage being controlled by a valve 65, and the passage 64 being controlled by a valve 66, each normally spring pressed 65 to its seat. Suitably mounted with relation to each valve or the stem thereof are suitable valve locking means, herein represented as cam levers 67 and 68 respectively, whereby the valves may be locked open when de- 70 sired.

In the present type of the invention, the lower portion of the compressor cylinder is connected by a vertical passage 69 with the lower portion of the cylinder of the pulsator, such passage being controlled by a valve 70, preferably spring pressed to its seat and provided with suitable means, as the cam lever 71, to lock the same in raised position. Preferably also the upper portion of the 80 compressor cylinder is connected by a passage (dotted lines Fig. 4) 72 with the upper portion of the cylinder of the pulsator, such passage being preferably controlled by a valve 73, herein represented as spring 85 pressed to its seat and having a cam lever or other device 74, whereby the valve may 90 be locked open. It is apparent that any suitable passages may be provided connecting desired portions of the compressor and pulsator whereby pressure may be built up, preferably at both ends of such pulsator. By the described passages and valves controlling the same herein represented for the 95

reversed if desired. Referring now more particularly to Figs. 4, 5 and 6, preferably upon the upper end 40 of the pulsator 40 and axially aligned therewith is secured what is herein designated as a compressor 58. Within the cylinder of the compressor is mounted for reciprocation a piston 59 having a piston rod 60 extending through a stuffing box 61 in the head plate 45 of the pulsator and connected to the piston 48 thereof, the cross-sectional area of the cylinder of the compressor herein being the same as the cross-sectional area of the trunk piston rod 49, so that herein the effective 50 area of the upper face of the piston 48 is equaled by the effective area of the lower face thereof plus the lower effective area of the piston 59 of the compressor, thereby producing balanced effective upper and lower 55 pressure areas for the pulsator piston.

purpose, when the building up of the air or 100 other fluid in the pulsator is required, the cam levers are thrown off from all the valve stems and the valves are worked according to the travel of the air into and out of the air compressor. Preferably a safety valve 105 75 is provided normally spring pressed to its seat and having if desired a cam lever or other device 76 whereby it may be locked open if desired. When the building up of the pressure is finished, or when such pressure begins to issue from the safety valve 75, the operator moves the cam levers 67 and 71 into the positions shown in Fig. 4, thereby locking open the valves 65 and 70. This 110 stops the building up of the pressure in the pulsator as the inlet air from the upper end of the compressor will then work back and forth through the inlet passage 62 passing 115 through the valve 65. In the action of the pulsator

Any suitable fluid may be employed in the pulsator but preferably compressed air is utilized, supplied in any suitable manner and herein preferably by means of the compressor whereby a pressure may be built up, and herein in both ends of the pulsator. For that purpose, I have herein represented an inlet for the air or other fluid (Fig. 4) 80 which is connected with the bottom of the valve 63. In the action of the pulsator the bottom stroke of the compressor will 120 work with the bottom stroke of the pulsator, thus transforming the compressor into a pulsator and balancing the area of the trunk portion of the pulsator as previously described. In order to permit the escape of 125 pressure from the system, all of the cam

levers for the different valves are brought into operative engagement with the valves, thus permitting the air or other fluid to pass out of the pulsator and out of the compressor. The connections 56 and 57 from the pulsator 40 are represented (Fig. 5) as connected to the working cylinder at 77 and 78 respectively, the upper portion of the working cylinder having passages 79, 79'

10 communicating with the connection 56 and the upper portion of said cylinder, whereby pressure may be admitted thereto.

By means of the passage 79 not only may pressure be admitted to the working cylinder to give the down or working stroke to the drills but a cushioning action may be afforded to prevent the piston 24 from striking the top head of the cylinder 26 in making its upward stroke. As shown in Fig. 5, 15 within the wall of the working cylinder is a vertically disposed passage 80 communicating at its lower end with the lower portion of the working cylinder and at its upper portion with the passage 79 when a suitably 20 mounted valve 81 (Figs. 5 and 6) is actuated for the purpose. While any suitable form of valve or valves may be employed and located as desired to control the pressure supplied to the opposite portions of the working 25 cylinder, I have herein indicated for the purpose a rotatably mounted valve having a passage 82 adapted to place a connection, as 56, from the pulsator in communication with the upper portion of the working cylinder or, when suitably actuated, in communication with the lower portion thereof, a suitable vent 83 (dotted lines Fig. 5) being provided and communicating with an axial vent 84 (Fig. 6) in said valve, whereby pressure 30 in the upper portion of said cylinder may be discharged.

It is frequently desirable to raise the cross head and drills supported thereby without raising the working cylinder. In the present embodiment of the invention, this is 45 preferably done by raising and holding elevated the piston 24 of the working cylinder. While any suitable mechanism may be employed for the purpose, I herein utilize the two-way valve 81 mounted in the working cylinder. At any time, when the pulsator is in operation, or when enough pressure is 50 in the pulsator to enable it to lift the piston 24, such piston may be raised and held elevated by turning the said two-way valve, so that the port 82 therein registers with the ports 79 and 80, the vent passage 84 in said valve being brought into register with the vent passage 83. The piston 24 therefore 55 will be held elevated until the two-way valve 81 is turned to register with the ports 79 and 79', whereby pressure is admitted to the upper face of said piston. When the piston 24 is thus raised the machine may be moved

along the track as the drills are thus elevated from the rock. If, for any reason, it becomes desirable or necessary quickly to elevate the cross head, as when the drills work loose therein, the two-way valve 82 may, in the manner described, be operated 60 without raising the working cylinder and without interrupting the action of the pulsator.

Having thus described one type or embodiment of my invention, I desire it to be understood that although specific terms are employed they are used in a generic and descriptive sense and not for purposes of limitation, the scope of the invention being set forth in the following claims. 80

Claims:

1. A machine having a body, a standard rising therefrom at the side thereof, a working cylinder mounted upon one face of said standard, a piston therein and a cross head controlled thereby, a pulsator secured to the opposite face of said standard and having fluid pressure connections with said working cylinder, a piston in said pulsator and operating means therefor. 90

2. A machine having a body, a standard rising therefrom, a working cylinder mounted upon said standard, means for moving said cylinder longitudinally thereof and including clutch controlled gearing, a pulsator secured to said standard and having fluid pressure connections with said working cylinder, a motor for operating said pulsator and driving connections from said motor to said clutch controlled gearing. 100

3. A machine having a body, a standard rising therefrom, a working cylinder mounted upon said standard for longitudinal movement, a piston therein and a cross head actuated thereby, gearing for longitudinally moving said cylinder, a pulsator mounted upon said standard and in fluid pressure connection with said working cylinder, a compressor in alignment with said pulsator, a motor for operating said pulsator, and driving connections between said motor and said gearing for imparting longitudinal movement to the working cylinder. 105

4. A quarrying machine comprising a body, a standard mounted thereon for movement longitudinally thereof, a pulsator mounted upon said standard, a working cylinder likewise mounted upon said standard, fluid pressure connections between said cylinder and pulsator and a driving motor for 115 said pulsator supported by the standard and adjustable thereon whereby in any position of said standard the driving motor may be positioned to permit operation of the machine with the standard close to the work. 120

5. A quarrying machine having a body, a standard mounted thereon for movement relative thereto, a working cylinder and

pulsator mounted upon said standard, a driving motor for said pulsator supported by the standard and adjustably mounted, whereby in any desired position of the standard the motor may be shifted to permit operation of the machine with the standard close to the work.

6. A machine having a body, an upright standard mounted thereon, a working cylinder upon said standard, and means upon the standard for moving said cylinder longitudinally of said standard said means including driving gearing, a motor, a clutch controlling said gearing and lever mechanism for actuating said clutch.

7. A machine having a body, an upright standard mounted thereon, a working cylinder mounted upon said standard for longitudinal movement, a screw shaft 28 operatively connected to said cylinder, and means upon said standard for turning said shaft, said means including a motor, gearing 29, 30 and 31, a clutch 34 for controlling said gearing, power driven gearing 33 operated by said motor for actuating said first named gearing, and lever mechanism 35, 36 and 38 for actuating said clutch.

8. A channeling machine having a truck, a standard adjustable thereon, a sliding frame on the standard, means for advancing or retracting the frame, cutting appliances on the frame directed to cut a groove at the side of the truck, a working cylinder to actuate said cutting appliances, also on said frame, a pulsator fixed on the standard, pressure-fluid connections between the working cylinder and the pulsator, and a motor also fixed on the standard for driving the pulsator.

9. A channeling machine having a truck, a standard adjustable thereon, a sliding frame on the standard, means for advancing or retracting the frame, cutting appliances on the frame directed to cut a groove at the side of the truck, a working cylinder to actuate said cutting appliances, also on said frame, a pulsator fixed on the standard, pressure-fluid connections between the working cylinder and the pulsator, and a motor for driving the pulsator.

10. A channeler having a truck, a standard adjustable thereon, a sliding frame on the standard, means for advancing and retracting the frame, cutting appliances on the frame directed to cut a groove at the side of the truck, pressure fluid pulsating means supported by the standard to reciprocate the cutting appliances, said means including a pulsating driving member and a working or driven member with means for transmitting pulsations from one to the other, and a motor fixed on the standard to drive the pulsating member.

11. A channeler having a truck, a stand-

ard adjustable thereon, a sliding frame on the standard, means for advancing and retracting the frame, cutting appliances on the frame directed to cut a groove at the side of the truck, pressure fluid pulsating means supported by the standard to reciprocate the cutting appliances, said means including a pulsating driving member and a working or driven member with means for transmitting pulsation from one to the other, and a motor supported by the standard to drive the pulsating member.

12. A channeling machine having a main frame, a standard, a frame longitudinally adjustable on said standard, means for feeding the frame thereon, a tool driving member exposed to confined working fluid, pulsating means for alternately raising and lowering the pressure of the confined working fluid at either side of said tool driving member, a motor supported by the standard and mechanical connections between the motor and the pulsating means.

13. A channeling machine having a main frame, a standard, a frame longitudinally adjustable on the standard, means for feeding the frame thereon, a tool driving member exposed to confined working fluid, pulsating means for alternately raising and lowering the pressure of the confined working fluid on either side of said tool driving member, a motor supported on the standard independently of said longitudinally movable frame, and mechanical connections between the motor and the pulsating means.

14. A channeling machine having a main frame, a standard, a frame longitudinally adjustable on the standard, means for feeding the frame thereon, a tool driving member exposed to confined working fluid, and pulsating means supported on the standard for alternately raising and lowering the pressure of the confined working fluid at either side of said tool driving member, a motor, and mechanical connections between the motor and the pulsating means.

15. A channeling machine having a main frame, a standard, a frame longitudinally adjustable on the standard, means for feeding the frame thereon, a tool driving member exposed to confined working fluid, pulsating means supported on the standard independently of said longitudinally movable frame for alternately raising and lowering the pressure in the confined working fluid at either side of said tool driving member, a motor, and mechanical connections between the motor and the pulsating means.

16. A percussive tool, its feed screw, a pulsator for operating the tool, the pulsator shaft, and manually controlled means for connecting and disconnecting the feed screw and pulsator shaft.

17. A truck, a base adjustable along the

same, a pulsator, a percussive tool operated thereby both mounted on the base, a feed screw for the tool, a motor, and driving connections between the motor and pulsator and the motor and feed screw.

18. A truck, a support adjustable along the same, a pulsator, a percussive tool operated thereby both mounted on the support, a feed screw for the tool, a motor, and driving connections between the motor and pulsator and the motor and feed screw.

19. A channeling machine having a truck, an angularly adjustable standard thereon, cutting appliances on said standard, feeding

means on said standard for moving said cutting appliances toward and from the work, a motor on said standard for operating said cutting appliances, a motor on said truck for moving said truck, and driving connections between one of said motors and said feeding means for actuating the latter.

In testimony whereof, I have signed my name to this specification, in the presence of two subscribing witnesses.

ALBERT BALL.
